UNITED STATES PATENT OFFICE

KEN HAYASHI, OF EVANSBURGH, ALBERTA, CANADA

LEAF HOLDER FOR BOOKS

Application filed July 15, 1929. Serial No. 378,531.

This invention relates to an improved accessory especially designed for use in association with books and constructed to maintain the halves of the book open and to retain the leaves open to facilitate reading, copying and the like.

The invention is in the nature of an attachment which is connected to and carried by the book to render it portable and it is 10 made to permit it to be applied to the book in a manner to take care of the increasing thickness and decreasing thickness of the halves as the pages are turned over from the beginning toward the end of the book.

15 In carrying the invention into effect, I have evolved and produced a simple and economical article which is susceptible of easy application and removal, which is not likely to tear the pages, which is out of the 20 way, easy to manipulate, and otherwise efficient in fulfilling the requirements of an article of this class in a satisfactory manner.

The particular details and their specific 25 association and arrangement will become more readily apparent from the following description and drawings.

In the drawings:

Figure 1 is a perspective view of a book, 30 showing it spread with the retaining device in operative position.

Figure 2 is a top plan view of the device itself as constructed in accordance with the present invention.

Figure 3 is an end view observing the 35 device in a position from left to right in Figure 1.

Figure 4 is a side view of the structure seen in Figure 3.

Figure 5 is a perspective view of one of 40 the parts of the device.

The major part of the device is in the nature of a frame and is generally designated by the reference character 6. I have found it expedient to provide a frame of 45 general U-shaped configuration, the bight portion of which is adapted to be located on the exterior of the adjacent end of the book, and the arms 8 and 9 of which are adapted to be inserted between the leaves 10 and 11 of the book, as observed in Figure 3.

The extremities of these arms 8 and 9 are pointed to facilitate insertion. On the center of the bight portion 7 is an outwardly projecting finger grip 12 of appropriate configuration.

The part 6 may be made from a small tube. At the points 13 and 14 are upstruck ears, these being located adjacent the center. At the opposite ends of the portion 7 are similar ears 15 and 16. These ears constitute spaced pairs of bearings in which rock shafts 18 and 19 are mounted for oscillation. In this way, I provide a pair of suitable clamp members 20 and 21, for cooperation with the opposite halves of the book. The inner ends are formed with laterally bent and appropriately shaped operating elements or handles 22 and 23. Then, too, at this point I provide retaining springs 24, of appropriate construction. The opposite ends of the shafts 18 and 19 are directed laterally and in parallelism with the arms 8 and 9. These end portions overlie the arms 8 and 9 and are of general arcuate configuration as indicated at 25, and 26, respectively.

These constitute the clamping fingers and it will be observed that they terminate in retaining balls 27 which rest upon the pages in the position seen in Figure 1.

These clamp members 20 and 21 are so 80 constructed and arranged as to permit the clamping fingers 25 and 26 to be swung back clear of the pages, so that the pages may be turned over without interference. This avoids tearing of the pages. Particularly, do I wish to emphasize the fact that these devices 20 and 21 are independently operable. Thus the leaves may be turned from either side of the book as desired, in accordance with the will of the user. Obviously, the handles 22 and 23 are arranged to cooperate with the finger grip 12 to facilitate the opening and closing of the respective clamping devices.

From the foregoing description and drawings it will be seen that I have evolved and produced an unusually simple and inexpensive contrivance which is susceptible of ready attachment and detachment, which is maintained on the book as long as desired 133.

and may be carried from place to place with the book. It holds the halves of the book open and maintains the pages or leaves flat down to facilitate copying, reading, etc. 5 The independent clamping devices are such as to facilitate manipulation and turning of the pages. It is thought, however, that by reading the description, a clear understanding of the invention, its construction, 10 method of use and features and advantages will be had. Therefore a more lengthy description is believed to be unnecessary.

15 Minor changes in the shape, size and rearrangement of details coming within the field of invention claimed, may be resorted to, in actual practice, if desired.

I claim:

- 20 1. As a new product of manufacture, a retainer of the class described comprising a substantially U-shaped member having its arm portions constructed for insertion between the leaves of an open book, a finger grip carried by the intermediate portion of the bight of said frame, a pair of individual clamping devices carried by said frame and having operating handles located for co-operation with said finger grip and also including leaf engaging fingers disposed over said arms.
- 25 2. In a structure of the class described, a substantially U-shaped attaching frame provided with pairs of longitudinally spaced bearings, pairs of individual leaf clamping devices each including a shaft mounted for oscillation in one pair of the bearings, each of said shafts being formed on its inner end with an operating handle and on its outer end with a curvate leaf engaging finger.
- 30 3. In a structure of the class described, a substantially U-shaped attaching frame provided with pairs of longitudinally spaced bearings, pairs of individual leaf clamping devices each including a shaft mounted for oscillation in one pair of the bearings, each of said shafts being formed on its inner end with an operating handle and on its outer end with a curvate leaf engaging finger.
- 35 4. In a structure of the class described, a substantially U-shaped attaching frame provided with pairs of longitudinally spaced bearings, pairs of individual leaf clamping devices each including a shaft mounted for oscillation in one pair of the bearings, each of said shafts being formed on its inner end with an operating handle and on its outer end with a curvate leaf engaging finger, and a terminal ball on the extremity of the finger.
- 40 5. In a structure of the class described, a substantially U-shaped attaching frame provided with pairs of longitudinally spaced bearings, pairs of individual leaf clamping devices each including a shaft mounted for oscillation in one pair of the bearings, each of said shafts being formed on its inner end with an operating handle and on its outer end with a curvate leaf engaging finger, and a terminal ball on the extremity of the finger.
- 45 6. In a structure of the class described, a substantially U-shaped attaching frame provided with pairs of longitudinally spaced bearings, pairs of individual leaf clamping devices each including a shaft mounted for oscillation in one pair of the bearings, each of said shafts being formed on its inner end with an operating handle and on its outer end with a curvate leaf engaging finger, and a terminal ball on the extremity of the finger.
- 50 7. In a structure of the class described, a substantially U-shaped attaching frame provided with pairs of longitudinally spaced bearings, pairs of individual leaf clamping devices each including a shaft mounted for oscillation in one pair of the bearings, each of said shafts being formed on its inner end with an operating handle and on its outer end with a curvate leaf engaging finger, and a terminal ball on the extremity of the finger.

In testimony whereof I affix my signature.

KEN HAYASHI.
